UNITED STATES PATENT OFFICE.

JOSEPH KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPING.

1,037,490.

Specification of Letters Patent. Patented Sept. 3, 1912.

Application filed January 3, 1912. Serial No 669,147.

To all whom it may concern:

Be it known that I, JOSEPH KELSO, a citizen of the United States, residing at Pittsburgh, in the county of Allegheny and State of Pennsylvania, have invented certain new and useful Improvements in Car-Couplers; and I do hereby declare the following to be a full, clear, and exact description of the invention, such as will enable others skilled in the art to which it appertains to make and use the same.

My invention relates to the construction of car couplers of the vertical plane type and is more particularly directed to the production of a strong, durable and efficient device of this character which, by reason of the compactness of its locking and knuckle opening mechanism, is especially well adapted for use upon passenger cars. Generally stated, I attain these objects by employing a horizontally slidable lock for the knuckle and by combining therewith a horizontally rotatable knuckle-opener lever, the lock being recessed or chambered to receive a spring which is interposed between said lock and the knuckle-opener lever, and the knuckle-opener lever being adapted to rotate into engagement with the lock to limit the expansion of the spring as well as to limit the forward movement of the lock when the knuckle is rotated to open position; and such a construction embodies the principal feature of my invention.

In the drawings illustrating my invention, the scope whereof is pointed out in the claims, Figure 1 is a view of a car coupler embodying my invention, a portion of the coupler head being shown in plan and a portion being shown in horizontal central section, and the knuckle, knuckle-opener and lock being shown in plan in locked positions; Fig. 2 is a front elevation of the construction shown in Fig. 1, the knuckle being removed and the lock and knuckle-opener being in locked positions; Fig. 3 is a detail vertical section taken on the line 3—3, Fig. 1; Fig. 4 is a detail view showing the knuckle-opener in plan and the knuckle, lock and a portion of the coupler head in horizontal central section, the parts being illustrated in the relation occupied when the coupler is locked; Fig. 5 is a detail horizontal section taken on the line 5—5, Fig. 2, the parts being shown in the positions occupied when the knuckle has been

rotated outwardly to open position; Fig. 6 is a detail sectional view illustrating the relation of the lock actuating device to the lock and to the coupler head; Fig. 7 is a detail vertical section taken on the line 7—7, 60 Fig. 6; Figs. 8 and 9 are detail perspective views of the lock; and Fig. 10 is a detail perspective view of the knuckle-opener.

Like symbols refer to like parts wherever they occur.

I will now proceed to describe my invention more fully, so that others skilled in the art to which it appertains may apply the same.

In the drawings, 1 is the coupler head and 70 2 is the knuckle, the coupler head being illustrated as of the type which is connected to the car through the intermediacy of a plurality of draft stems, and the knuckle being preferably pivotally connected 75 to the head in the usual manner by means of a knuckle pin 3. The center draft stem 4, which may be conveniently formed in two parts so as to embrace a portion of the coupler head, is preferably connected to the 80 latter by means of a pivot pin or bolt 5. Lugs 1^a, 1^a and 1^b, 1^b, which project laterally from the coupler head afford means for pivotally connecting the side stems of the coupler to the coupler head. 85

Slidably mounted in the coupler head 1 is a horizontally movable lock or catch 6 which, when in locked position, serves to prevent the outward rotation of the knuckle 2. This lock member is formed with a 90 spring pocket or chamber 6^a that is adapted to receive a coiled spring 7 one end of which rests upon the catch 6 and the other end of which bears upon a rotatable knuckle opener lever 8. As more particularly shown in Fig. 5, the rearward or unlocking movement of the lock 6 is limited by the engagement of the shoulders 6^b of the latter with the corresponding stop faces 1^c of the coupler head. The unlocking movement of the lock 6 may 100 be conveniently effected through the instrumentality of a bell-crank unlocking lever 9 which may be pivotally mounted beneath the coupler head on the bolt or pivot pin 5 by which the center stem 4 is connected 105 to the coupler head, said unlocking lever being provided with a lock-actuating pin 9^a which extends upwardly through an arcuate slot 1^d in the lower wall of the coupler head and enters an opening or recess 6^c formed 110

in the lock 6^c, the recess 6, as shown, being elongated transversely so as to allow the lock to move rectilineally while the unlocking lever 9 is turning upon its pivot. The locking movement of the unlocking lever, as well as of the lock 6, is arrested by the engagement of the portion 9^b of the unlocking lever with a stop or lug 1^e which is formed on the under side of the coupler head adjacent to the forward end of the arc shaped slot 1^d therein. The knuckle 2 is rotated to open or coupling position by means of a horizontally rotatable knuckle-opener lever 8 which is pivotally mounted in the coupler head 1 by means of a pin or bolt 10. The inner end of the knuckle-opener, or end upon which the spring 7 bears, is preferably formed with a tapering stud 8^a which extends into the interior of the spring and thus prevents the latter from becoming accidentally disassociated from the knuckle-opener when the coupler is in service. The outer end, 8^b, of the knuckle-opener extends behind the tail 25 of the knuckle 2 and operates to impart an opening rotation thereto when the spring 7 is energized by an unlocking movement of the lock 6 and the knuckle is free to rotate outwardly. For convenience of manufacture and ease of assembly, the opening in the lever 8 for the reception of the pivot pin 10 is, as more particularly shown in Fig. 10, preferably formed as a slot 8^c leading in from the rear face of the knuckle-opener. 30 In order to attain a compact arrangement of parts the forward end of the lock 6 is preferably formed with a recess 6^e which is adapted to receive the inner or lock-engaging end of the tail of the knuckle 2; and 35 the side of the lock 6 which is adjacent to the knuckle-opener lever 8 is recessed or slotted to receive a portion of the knuckle-opener, as more particularly shown in Figs. 4, 5 and 8. 40 Projecting upwardly from the upper face of the knuckle-opener 8 is a lug 8^d which, as shown in Fig. 5, is adapted to move into the path of locking movement of the lock 6 and to engage the inclined face 6^d upon the adjacent side thereof when the knuckle-opener lever has performed its knuckle opening rotation. This engagement of the lug 8^d with the face 6^d of the lock not only serves to limit the outward rotation of the 45 knuckle-opener 8 but also serves to limit the outward or locking movement of the lock 6, the extent of expansion of the spring 7 being thus jointly controlled by the lock and knuckle-opener and all liability of it jumping out of its receiving chamber 6^a in the lock 6 or becoming unseated from the knuckle-opener 8 being thus overcome.

The construction and arrangement of the several elements of the coupler being substantially such as hereinbefore pointed out,

the operation of the device will be as follows: Assuming the parts to be in locked or coupled position, as illustrated in Figs. 1, 2, 3, 4, 6 and 7, an unlocking rotation of the bell-crank lever 9 causes the lock 6 to slide rearwardly, thus compressing the coiled spring 7. When the lock 6 has been withdrawn sufficiently to permit the knuckle 2 to rotate outwardly, the spring 7 expands, thus rotating the knuckle-opener lever 8 around its pivot pin 10 and causing the outer end 8^b of the knuckle-opener to impart a strong rotative impulse to the tail of the knuckle 2, thereby impelling the knuckle to rotate to open or coupling position as illustrated in Fig. 5. When the knuckle 2 is rotated inwardly to locked or coupled position from the coupling position, shown in Fig. 5, the rear face of the tail of the knuckle 2 engages the outer end 8^b of the knuckle-opener 8, forcing the latter to rotate upon its pivot pin 10. As the inner end 2^a of the knuckle tail prevents the lock 6 from moving forwardly while the knuckle-opener is being forced rearwardly by the knuckle, this rotation of the knuckle-opener 8 causes the spring 7 to be energized, so that when the knuckle 2 has rotated inwardly sufficiently far to permit the lock 6 to move forwardly the latter will be forced to locked position and there maintained against accidental unlocking by the spring 7.

I claim:

1. In a car coupler, the combination with a coupler head, of a knuckle pivotally mounted thereon, a lock for said knuckle, a knuckle-opener lever movably mounted on said coupler head, a spring operatively interposed between said lock and said knuckle-opener lever, and coacting means upon said lock and said knuckle-opener lever that are movable into engagement to limit the extent of movement of the lock in a locking direction when the knuckle is rotated to open position.

2. In a car coupler, the combination with a coupler head, of a knuckle pivotally mounted thereon, a horizontally slidable lock for said knuckle, a horizontally rotatable knuckle-opener lever pivotally mounted on the coupler head, said lock being slotted to receive said knuckle-opener, a spring interposed between said lock and knuckle-opener, and a lug on said knuckle-opener which is adapted to move into engagement with the lock to limit the movement of the latter toward locked position when the knuckle is rotated to open position.

3. In a car coupler, the combination with a coupler head, of a knuckle pivotally mounted thereon, a horizontally slidable lock for said knuckle, said lock having an inclined face, a knuckle-opener lever pivotally mounted on the coupler head, and a spring interposed between said lock and

knuckle-opener, and a lug on said knuckle opener lever which is adapted to move into engagement with the inclined face of said lock to thereby limit the movement of the latter toward locked position when the knuckle is rotated to open position.

4. In a car coupler, the combination with a coupler head, of a knuckle pivotally mounted thereon, a lock for said knuckle 10 slidably mounted on the coupler head, a knuckle-opener lever, a pivot pin on which said knuckle-opener is rotatably mounted, a spring interposed between said lock and knuckle-opener, said lock being slotted to 15 receive a portion of the knuckle-opener and being recessed to receive the inner end of

the tail of the knuckle, and said knuckle-opener being slotted to receive a pivot pin, and a lug on said knuckle opener lever which is adapted to extend into the path 20 of movement of and to engage the lock to thereby limit the movement of the latter toward locked position when the knuckle is rotated to open position.

In testimony whereof I affix my signature, in the presence of two subscribing witnesses.

JOSEPH KELSO.
